4-(DIMETHYLAMINOETHYLAMINO)-6-METHOXY QUINOLINE AND SALTS THEREOF

Charles F. Geschickter, Kensington, and Leonard M. Rice, Baltimore, Md.

No Drawing. Application June 7, 1955,
Serial No. 513,906

3 Claims. (Cl. 260—286)

The present invention relates to new quinoline derivatives, to non-toxic salts thereof, and to methods of making these compounds. More particularly our invention relates to a 4-dimethylaminoethylamino-6-methoxy quinoline and to non-toxic salts thereof which we have found to be effective remedies for asthma and related allergic disorders.

This application is a continuation-in-part of application Serial No. 378,420 filed September 3, 1953, which is a continuation-in-part of application Serial No. 251,980 filed October 18, 1951. It is also a continuation of applications Serial No. 378,422, filed September 3, 1953, and Serial No. 446,946 filed July 30, 1954, and a continuation-in-part of Serial No. 379,781, filed December 11, 1953.

We have found that 4-dimethylaminoethylamino-6-methoxy quinoline has bronchial dilator and antihistaminic action and that it tends to concentrate in the respiratory tissues. For this reason, the compound is effective in the treatment of asthma. While this base compound is insoluble in water it may be administered orally in oil solutions and we have found that it has a cumulative effect and is characterized by long retention in the body.

Non-toxic salts of the base have the same bronchial dilator and antihistaminic action and have other desirable properties which make them easier or more convenient to administer and improve the safety factor for administration. All of the non-toxic salts have the bronchial dilator and antihistaminic action but due to their other properties, the salts fall into different groups.

The non-toxic inorganic salts such as the chloride, bromide, iodide, phosphate and sulphate are very soluble in water but they are acidic and painful when administered by injection. Complex organic salts such as the salts of phthalamic, quinic, nicotinic, and ascorbic acids and theophylline are soluble, substantially neutral, have low toxicity and because of their relatively high molecular weights have a relatively high safety factor. The non-toxic simple organic salts such as the acetate, tartarate, myristate and stearate have properties which are in general between those of the inorganic salts and those of the complex organic salts. The simple organic salts are generally less acidic than the inorganic salts and, as the molecular weight increases, they become less soluble in water and more soluble in oils.

An important object of the present invention is to provide as a novel composition of matter, 4-dimethylaminoethylamino, 6-methoxyquinoline and non-toxic salts thereof.

Another object is to provide quinoline compounds which are a remedy for asthma and related allergic disorders.

Another object is to provide water-soluble, non-toxic quinoline compounds.

Another object is to provide non-toxic quinoline compounds which are substantially neutral.

Another object is to provide non-toxic quinoline compounds which are substantially stable and moisture proof.

Another object is to provide methods of making 4-dimethylaminoethylamino-6-methoxy quinoline and non-toxic salts thereof.

The free base form of the compounds of the present invention is 4-dimethylaminoethylamino-6-methoxyquinoline which has the following formula:

This new quinoline derivative and its non-toxic salts have been tested in over 500 patients and have been found to be effective in the treatment of asthma and related allergic disorders. The compounds have been found to have anticholine and antihistaminic effects and to be concentrated in the lungs and respiratory tissues. Their characteristics include long retention in the body and a cumulative effect so that when used in the treatment of asthma, relief is prolonged and dosage may be reduced as the treatment progresses. Another important property of the new compound and its salts is low toxicity and absence of undesirable side effects.

The free base may be prepared as follows:

I.—Alpha-carbethoxy-B-(p-anisidino)-acrylate

A mixture of 0.4 mole of p-anisidine and 0.4 mole of ethoxymethylene malonic ester was heated at 130 deg. until no more bubbles of alcohol could be detected coming from the mixture.

II.—3 carbethoxy-4-hydroxy-6-methoxyquinoline

To 1000 cc. of boiling dowtherm was added 0.4 mole of I above. The solution was heated under reflux for 45 minutes, allowed to cool and was diluted with 1000 cc. of high-boiling petroleum ether. The light colored solid was filtered and washed twice with carbon tetrachloride, then twice with petroleum ether and twice with ether. After boiling with 50% ethanol the product has a melting point of 273-277 deg. The product can be crystallized also from cyclohexanone.

III.—3-carboxy-4-hydroxy-6-methoxyquinoline

The ester group was removed by boiling with 18% hydrochloric acid for one hour. The solution was filtered and the desired free acid crystallized as the filtrate cooled. Melting point 271 with gas evolution.

IV.—4-hydroxy-6-methoxyquinoline

The acid from III above was heated in a Wood's metal bath at 275 deg. until the evolution of carbon dioxide ceased. The product was taken up in hot water (20 ml. per gram) and treated with decolorizing charcoal. This hot mixture was filtered and the product crystallized from the filtrate in the form of needles. Melting point 240-243 deg. The product in solution gives a pink or red color with a drop of ferric chloride solution.

V.—4-chloro-6-methoxyquinoline

The 4-hydroxy-6-methoxy quinoline was refluxed with phosphorus oxychloride for 4 hours. After cooling the reaction mixture was hydrolyzed by pouring onto cracked ice and the resulting aqueous suspension made alkaline with sodium hydroxide. The insoluble product was filtered, washed with water and dried. Melting point 80-81 deg.

VI.—4-(B-dimethylaminoethyl)-6-methoxyquinoline

4-chloro-6-methoxy quinoline (0.205 mole) and B-dimethylaminoethylamine (0.200 mole) were heated slowly in a bomb tube with a crystal of K. I. to 145 to 150 deg. for 4 hours. The reaction mixture was transferred with the aid of a little dilute hydrochloric acid to 500 ml. of water. The solution was extracted with a little ether and next was neutralized with sodium hydroxide until strongly basic. The basic solution was extracted twice with ether and the extract was dried over magnesium sulfate and

concentrated from a water bath. Upon slurring with petroleum ether oil solidified and was recrystallized from high boiling petroleum ether. Melting point 107-109. A better product may be obtained by distillation at a pressure of less than 1 mm.

The 4-dimethylaminoethylamino 6-methoxy quinoline is an almost white crystalline powder which is insoluble in water but is soluble in common organic solvents such as alcohol, benzene, ether, chloroform and the like. Upon analysis it showed the following content:

	C	H	N
Theoretical.....	68.54	7.8	17.13
Found.....	68.42	7.65	17.32

The free base may be administered orally in an alcohol or oil solution. It is absorbed into the system and ultimately concentrates in the lungs and bronchial tissues. In this form, absorption is slow but since the effects are cumulative, the free base is effective in relieving asthma.

The non-toxic organic and inorganic salts are as effective as the base compound and generally have the additional desirable property of being more soluble, and hence, more convenient to administer. Non-toxic inorganic salts include the chloride, bromide, iodide, sulphate and phosphate and non-toxic organic salts include the acetate, citrate, tartarate, stearate, myristate, phthalate, naphthalate, succinate and salts of theophyllin, phthalamic acid, quininic acid, nicotinic acid, ascorbic acid and the like.

To prepare the inorganic salts, the appropriate acid in alcohol solution is added to an alcohol solution of the base. The salt is then precipitated with ether and recrystallized. The hydrochloride for example is a yellowish hydroscopic crystalline solid with an indefinite melting point. It is soluble in alcohol and very soluble in water.

The inorganic salts have a high pH value and are painful when administered by injection. Neutralizing the pH value with a base may precipitate the free base. These salts are also hydroscopic so that handling and storage presents a problem.

The simple organic salts such as the acetate, stearate, and myristate are prepared in a similar manner. An alcohol solution of the chosen organic acid is added to an alcohol solution of the base in molar proportions. The alcohol is then distilled off at reduced pressure.

The acetate is a buff colored crystalline powder very soluble in water and soluble in alcohol, benzene, ether and oily vehicles. It has an indefinite boiling point. The stearate is a yellowish oil insoluble in water but soluble in common organic solvents. The myristate is an oil and is soluble in sesame oil and common organic solvents but not very soluble in water.

Some of these simple organic salts are very stable and moisture resistant. Because of this property they may be manufactured, shipped and stored in bulk or tablet form without damage or deterioration.

The more complex organic salts such as the salts of theophylline, quininic acid, phthalamic acid, nicotinic acid and ascorbic acid are soluble, substantially neutral and often have a lower toxicity than the base compound. These salting radicals also have some bronchial dilator action so that these salts are more effective and easier to administer than the base compound.

Because of their relatively high molecular weights, the more complex organic salts also have a greater factor of safety. The salting radical has substantially no toxicity and variations in dosage will have a relatively minor effect on the amount of base compound administered.

Preparation of the theophylline salt of 6-methoxy-4-dimethylaminoethylamino quinoline

A mixture of 29.6 grams of theophylline and 24.5

grams of 6-methoxy-4-(dimethylaminoethylamino) quinoline are dissolved in 200 ml. of dry acetone. The solution after filtering is transferred to a 3-liter container and the acetone is removed under reduced pressure. After most of the acetone has been removed, the last traces are removed under high vacuum. The residue is covered, redissolved in alcohol, from which it is obtained as a crystalline salt.

10 4-(dimethylaminoethylamino)-6-methoxyquinoline salt of quininic acid

A mixture of 2.45 gr. of 4-dimethylaminoethylamino-6-methoxy quinoline and 4.06 gm. of quininic acid is heated at reflux with 35 cc. of dry acetone. Methanol (anhydrous) is added to the boiling solution until the material just dissolves. The solution is boiled an additional several minutes and filtered. The solution is allowed to come to room temperature and diluted to permanent turbidity with anhydrous ether. Upon standing in the ice box for several hours there is obtained 5 gm. of the salt (77%) in the form of needles which after filtration and drying melts at 162-163. The salt dissolves in water giving an almost neutral solution.

25 The N,N-diethyl cis- Δ^4 tetrahydrophthalamate salt of 6-methoxy-4-(dimethylaminoethylamino) quinoline

A mixture of 45.5 grams (0.2 mol) of N,N-diethyl cis- Δ^4 -tetrahydrophthalamic acid and 25.5 grams (0.1 mol.) of 6-methoxy-4-(dimethylaminoethylamino) quinoline are dissolved in 200 ml. (a convenient quantity) of dry acetone. The solution, after filtering is transferred to a container of suitable size and the acetone removed under reduced pressure. After most of the acetone has been removed the last traces are removed under high vacuum (less than 0.1 mm.). The residue is loosely powdered, transferred to a mortar and finely powdered. The product is an almost white, free flowing hygroscopic powder.

In the process illustrated in the foregoing example, the following amic acids may be used in place of N,N-diethyl cis- Δ^4 -tetrahydrophthalamic acid to obtain the corresponding salts:

- 45 N,N-dimethyl phthalamic
N,N-diethyl phthalamic
N,N-dimethyl hexahydrophthalamic
N,N-diethyl hexahydrophthalamic
N,N-dimethyl cis- Δ^4 -tetrahydrophthalamic

The process is the same as described in the above example for all the amic acids listed:

50 Methods for preparing the substituted amic acids of the type listed above are fully disclosed in copending application Serial No. 378,417 filed September 3, 1953.

55 Ascorbic acid salt of 4-(dimethylaminoethylamino)-6-methoxy quinoline

To prepare this salt, 7.04 grams (0.04 mole) of ascorbic acid dissolved in 100 ml. of methanol was placed in a 500 ml. flask fitted with a condenser. To this was added 60 4.9 grams (0.08 mole) of 4-(dimethylaminoethylamino)-6-methoxy quinoline dissolved in 25 ml. of methanol. The mixture was refluxed for one hour and the methanol distilled off in a water bath. The product was obtained as a yellow crystalline powder, very soluble and giving a neutral solution in water.

65 The nicotinic acid salt was prepared in substantially the same manner.

The complex organic salts such as the phthalamate, ascorbate and the like may be administered orally or by injection. For oral administration, the salts are given in 70 50 mg. tablets or capsules once or twice daily. For parenteral administration, the salt may be dissolved in water, benzyl alcohol and diethyl hexahydrophthalic ester solution, or a suitable oil such as peanut oil, sesame oil or the like and injected intramuscularly. A convenient solution

is 100 to 120 mg. per cc. and dosages of $\frac{1}{2}$ cc. daily have been found effective and, since the results are cumulative, administration can be reduced to every other day or even weekly as indicated by the patient's response to the treatment. Since the 4-(dimethylaminoethylamino)-6-methoxy quinoline is the primary active portion of the compound, dosages and concentrations of the base compound and other salts are varied so that substantially the same amount of the active portion is given.

From the foregoing it will be apparent that we are able to accomplish the objects of our invention and provide novel compounds which have valuable therapeutic properties and a process for producing such compounds. Various modifications can of course be made without departing from the spirit of the invention or the scope of the appended claims. The term acid addition salts used in the claims

refers to salts of the type formed by treating a base with an acid.

We claim:

1. As a new composition of matter the ascorbic acid salt of 4-(dimethylaminoethylamino)-6-methoxy quinoline.
2. As a new composition of matter the nicotinic acid salt of 4-(dimethylaminoethylamino)-6-methoxy quinoline.
3. A novel composition of matter consisting of a compound selected from the class consisting of 4-(dimethylaminoethylamino)-6-methoxy quinoline and non-toxic, water soluble acid addition salts thereof.
